Primary Examiner — Barbara Fox*Assistant Examiner* — Harold E Blackwell, II(74) *Attorney, Agent, or Firm* — Laurence P. Colton; Smith Tempel Blaha LLC(57) **CLAIM**

The ornamental design for a blind chain tensioner as shown and described.

DESCRIPTION

FIG. 1 is an upper side perspective view of the blind chain tensioner of the present design.

FIG. 2 is a front view thereof.

FIG. 3 is a right side view thereof.

FIG. 4 is a left side view thereof.

FIG. 5 is a bottom view thereof.

FIG. 6 is a top view thereof; and,

FIG. 7 is a rear view thereof.

The broken line showing of the blind chain tensioner is for the purpose of illustrating portions of the article and forms no part of the claimed design.
